WAVE FORMING AND SETTING DEVICE

William Huppert, New York, N. Y., assignor to
Delamere Company, Inc., a corporation of Del-
aware

Application January 26, 1939, Serial No. 252,860

15 Claims. (Cl. 132—31)

This invention relates to hair wave forming and setting devices, and more particularly to a combined comb and hair clamp.

An object of this invention is to provide a hair device of this character in which the comb is disposed between the clamp elements and so interconnected therewith that upon opening the jaws of the clamp, the comb is automatically projected to an operative position below the ends of the opened jaws, and upon closing the jaws, said comb is automatically retracted.

A further object is to provide a construction whereby the comb is directed and guided in a plane bisecting the angle through which the jaws move at all times during the projective or the retractive movements of the comb.

Another object of this invention is to provide a wave forming and setting structure which has few structural parts, is easy to manufacture, and relatively simple to assemble.

Other objects and advantages of my invention will become apparent as the description thereof proceeds, reference being had to the accompanying drawing, in which:

Figure 1 is a side elevation of the device;

Fig. 2 is an enlarged sectional view thereof taken on the line 2—2 of Fig. 3 showing the comb element in its retracted position;

Fig. 3 is a sectional view thereof taken on the line 3—3 of Fig. 2;

Figs. 4 and 5 are enlarged sectional views taken on the line 4—4 and line 5—5, respectively, of Fig. 2;

Fig. 6 is an enlarged sectional view similar to Fig. 5, showing the clamp open and the comb element in its projected position;

Fig. 7 is a view of a modification with parts of the clamp broken away, taken on the line 7—7 of Fig. 8; and

Fig. 8 is a fragmentary sectional view of the same modification taken on the line 8—8 of Fig. 7.

The device comprises a comb or toothed element 10 which is attached to supporting plates or arms 11 and 12. It is contemplated that the comb 10 and the arms 11 and 12 may be made either integral or of separate parts connected together, and that any suitable materials may be used for such construction. The shape and construction of these plates or arms is best seen in Fig. 6. They may each have a vertical slot 13 and two horizontal slots 14 and 15 for the purpose to be hereinafter described.

The clamp structure comprises two similar pivotally connected clamp members indicated generally as 16 and 17. The member 16 has a

handle portion 18 and two ears 20 and 22, one at each end, bent at right angles thereto. At its lower portion is the wave clamping jaw 24 with the outwardly flared portion 26 and stamped out teeth 28.

The clamp member 17 is constructed similarly to member 16 with handle portion 19, right angle ears 21 and 23, clamping jaw 25, flared portion 27 and teeth 29.

The jaw portions 24 and 25 just above the teeth 10 are bent outwardly to provide a space or a pocket, as clearly shown in Figs. 4 and 5, in which the comb is received when in its normal retracted position.

The two members 16 and 17 are counterparts 18 in form and construction but are reversed in position in assembly. This reduces the number of different parts that have to be made and provides an economical structure.

The clamp members 16 and 17 are pivotally 20 mounted on a pin 30 which passes freely through openings 31 arranged centrally in the overlapping ears 20, 21, 22, 23. This pin 30 also passes through the vertical slots 13 in the comb supporting arms 11 and 12, which slots provide the 25 necessary clearance to permit up and down movement of the comb relative to the pivot of the clamp jaws. The ears 20 and 22 are also provided with arcuate slots 32, 34, respectively, and ears 21 and 23 are similarly provided with 30 arcuate slots 33, 35, respectively.

36 is a pin which is fixed to move the ears 20 and 22 of the clamp member 16 which pin passes through slots 33 and 35 of ears 21 and 23 of the companion clamp member 17, as well as 35 through horizontal slots 15 of both comb carrying members 12.

Correspondingly, a pin 37 is fixed to move with the ears 21 and 23 of clamp member 17 and passes through slots 32 and 34 of ears 20 and 22 40 of the other clamp member and through horizontal slots 14 of both comb carrying members 12.

A spring 38 surrounds the pin 30. Its ends are so shaped as to permit of free movement of pins 45 36 and 37 during operation of the device. These looped ends bear on the clamp members 16 and 17 to urge them normally closed.

In use, the operator grasps the handles 18 and 19 and presses them toward each other to open 50 the clamp members 16 and 17, as shown in Fig. 6. The pin 36, rotatable with clamp member 16, and the pin 37, rotatable with clamp member 17 will be moved downwardly from the position shown in Fig. 5 to that shown in Fig. 6 and will 55

carry with them the comb supporting members 11 and 12 and the comb 10. The comb is thus automatically moved and guided downwardly beyond the ends of the teeth 28 and 29 into its projected or operative position and through a plane that bisects the angle of movement of the clamp jaws. Since the comb extends a considerable distance below the ends of the jaw teeth 28 and 29 in the open position of the clamp, the comb may 10 be safely used without danger of the hair being caught in the teeth of the jaws.

The comb in its extended position is drawn through the hair to the point where the wave is to be formed, the hair preferably having first 15 been dampened. At this point the device, with the comb engaged in the hair, is shifted lengthwise in the direction in which the wave is to be formed. The clamp arms 16 and 17 are then released and are closed by the action of the spring 20 33. In their closing motion, the clamp jaws gather the hair and raise it in ridge form, and the comb 10 is automatically withdrawn from the hair by the mechanism described above. The clamp holds the raised wave in form until the 25 hair is dry and set.

In the modified construction shown in Figs. 7 and 8, each comb carrying arm 39 is formed with a notch 40 in which the pivot pin 30 rides during the up and down movements of the comb 10. 30 In this instance, in lieu of having pivot pins 36 and 37 extending longitudinally across the handle portions of the jaws, each comb carrying arm 39 is provided with two outwardly extending studs 41 and 42, and instead of forming slots 14 and 35 45 in said arms, corresponding slots 43 are formed in the overlapping ears 20, 21 and 22, 23 of the clamp members 16 and 17. Said ears are also provided with curved slots 44 and 45 which are of somewhat different curvature from that of 40 the arcuate slots 34 and 35 but which function in a similar manner in guiding the arms in their upward and downward movement. In this form, as well as in the form previously described, the opening movement of the jaws automatically 45 projects the comb 10 downwardly, and the closing movement thereof retracts it to the position shown in Fig. 7.

One or the other of the studs 41, 42 with the corresponding slots in the ears, may be omitted. 50 However, in that case, while the device would operate in the same manner, the two jaw members of the clamp would have to be manufactured separately as they would not be counterparts. 55 Various other modifications of the structure hereinabove described may be made within the scope of the invention as defined in the claims.

What I claim is:

1. In a hair wave forming and setting device, a 60 pair of pivotally connected clamp jaws, a toothed member disposed between said jaws, means connecting the toothed member to the clamp operative to move said member automatically downward relatively to the pivotal point of the jaws 65 to a position below the lower ends of said jaws upon opening the clamp and to retract said member upon closing the clamp.

2. In a hair wave forming and setting device of the character described, toothed means for 70 forming a wave, means for clamping and holding the wave after it is formed, and means actuated by the clamping and holding means in its closing motion to retract the wave forming means from its wave forming position, said clamping 75 and holding means acting to extend the wave

forming means to its wave forming position upon the opening motion thereof.

3. In a hair wave forming and setting device of the character described, a comb for forming the wave, clamping members cooperating with said comb for clamping and holding the wave after it is formed, and means actuated by the clamping members upon their closing motion to retract the comb from its wave forming position.

4. In a hair wave forming and setting device of the character described, a comb for preparing the hair and forming a wave therein, clamping means cooperating with said comb for clamping and holding the wave after it is formed, means actuated by the clamping means for retracting the comb from its wave forming position upon actuation of the clamping means towards closing position, and means actuated by the clamping means for extending the comb to its wave forming position upon actuation of the clamping means toward open position.

5. In a hair wave forming and setting device of the character described, a comb for preparing the hair and forming a wave therein, clamping means cooperating with said comb for clamping and holding the wave after it is formed, means actuated by the clamping means for retracting the comb from its wave forming position upon actuation of the clamping means towards closing position, said clamping means acting to extend the comb to its wave forming position upon its actuation toward open position.

6. In a device of the character described, a comb, two pivotally connected jaw members forming a clamp, said members being disposed on opposite sides of the comb, a pocket formed between said members when in the closing position for receiving the comb, and means operative automatically upon the opening of said clamp to project said comb from said pocket.

7. In a device of the character described, a comb, arms connected to said comb, a plurality of slots in each arm, a clamp having a pair of jaw members between which the comb is disposed, a pin passing through said clamp members upon which they are rotatable, a second pin connected to each clamp member to move therewith, said pins cooperating with said slots in said arms to extend and retract said comb and to guide it in its motion as said clamp members are opened and closed.

8. In a device of the character described, a comb, arms connected to said comb, a plurality of slots in each arm, a clamp having a pair of jaw members between which the comb is disposed, a pin passing through said clamp members upon which they are rotatable, a second pin connected to each clamp member to move therewith, a spring acting on said clamp members to urge them closed, said pins cooperating with said slots in said arms to extend and retract said comb and to guide it in its motion as said clamp members are opened and closed.

9. In a device of the character described, a comb, a clamp having a pair of cooperative jaw members between which the comb is disposed, said clamp members being pivoted on a pin to rotate thereon, said comb being connected to arms having vertical and horizontal slots, said pin passing through said vertical slots to provide 70 guiding means and to allow relative motion between said pin and comb, a pin connected to move with each clamp member, said latter pins cooperating with said horizontal slots in said arms to allow relative motion between said latter pins. 75

and the pivot pin, whereby as said clamp members are opened or closed said comb is automatically projected or retracted respectively.

10. In a device of the character described, a comb, a clamp having a pair of cooperative jaw members between which the comb is disposed, said clamp members being pivoted on a pin to rotate thereon, said comb being connected to arms having vertical and horizontal slots, said pin passing through said vertical slots to provide guiding means and to allow relative motion between said pin and comb, a pin connected to move with each clamp member, said latter pins cooperating with said horizontal slots in said arms to allow relative motion between said latter pins and the horizontal slots of said arms, an arcuate slot in each clamp member, the pin that is connected to move with one clamp member passing through the slot of the other clamp member thereby providing for relative motion between the clamp members without interference of their pins, said pins and slots cooperating to project said comb as said clamp members are opened and to retract said comb as said members are closed.

25. 11. In a device of the character described, a clamp having a pair of angularly movable pivotally connected jaws, a vertically movable comb disposed between said jaws, and means cooperating with said jaws to guide and direct the movement of the comb in a plane bisecting the angle between the two jaws at all angular positions of the jaws during the opening or closing movement thereof.

30. 12. In a device of the character described, a clamp having a pair of angularly movable pivotally connected jaws, a comb disposed between said jaws, means for guiding the comb in a plane bisecting the angle between the two jaws at all angular positions of the jaws during the opening

or closing movement thereof, and means for advancing the comb during the opening movement of the jaws and for retracting it during the closing movement.

13. In a device of the character described, a clamp comprising a pair of jaw members, resilient means acting on the jaws to maintain them normally closed, a comb disposed between the jaws, supporting arms carrying the comb, a pin on which the jaws are pivoted which pin passes through an opening in the arms, each of said arms having a pair of studs that pass through slots in the clamp members, said studs and slots cooperating to guide the comb throughout its path of movement and to project or retract it automatically as the clamp is opened or closed.

14. In a device of the character described, a clamp comprising a pair of jaw members, resilient means acting on the jaws to maintain them normally closed, a comb disposed between the jaws, supporting arms carrying the comb, a pin on which the jaws are pivoted which pin passes through an opening in the arms, each of said arms having at least one stud that passes through a slot in each clamp member, said stud and slots cooperating to guide the comb throughout its path of movement and to project and retract it automatically as the clamp is opened or closed.

15. In a device of the character described, a clamp comprising a pair of pivotally connected jaw members, a comb disposed between the jaws, supporting arms carrying the comb, each of said arms having at least one stud that passes through a slot in each clamp member, said stud and slots cooperating to guide the comb throughout its path of movement and to project and retract it automatically as the clamp is opened or closed.

WILLIAM HUPPERT.
